ABSTRACT: A marking tag is secured to an article, such as a garment, by a nondamaging fine wire sandwiched between layers of backup material and cover material. Facilities are provided for folding a backup layer of sheet material over the edge of the article with portions of the layer on each side of the article. A hollow needle housing the fine wire is then passed through the backup layer and article therebetween and the needle is removed leaving the wire in the article. Facilities are provided for then bending the wire parallel to the article on each side so that the ends of the wire extend generally toward the edge of the article. A cover layer having a surface of heat sealable adhesive is then superposed and adhered over the backup layer on each side of the article to enclose and anchor the ends of the wire therebetween. The tag is removed by pulling the sheet material away from the article so that the wire tears through the backup layer to free one end of the wire, whereupon on continued pulling, the freed end of the wire is withdrawn from the article.

**MACHINE FOR ASSEMBLING AND ATTACHING A TAG
TO AN ARTICLE**

BACKGROUND OF THE INVENTION

In the past there have been numerous devices available for marking and identifying articles which in one form or another were clipped, tied, bonded, pinned, stapled, or otherwise secured to the article. These prior known devices have been objectionable for one or more of the following reasons: (1) expensive, (2) damaging to the article, (3) difficult to secure or release, (4) subject to surreptitious removal and insertion onto another article, (5) existence of sharp edges which presented a safety problem, (6) or could not withstand vigorous agitation.

The subject invention relates to a machine which assembles and attaches a tag to an article in such a way that all of the above problems which existed in the prior art have been obviated. The subject machine reliably and inexpensively assembles and attaches a marking tag to an article, and additionally prints indicia on one face of the tag for later identification of the article.

CROSS-REFERENCE TO RELATED APPLICATION

This application relates to a machine for assembling and attaching marking tags which are disclosed and claimed in application Ser. No. 629,303 filed on Apr. 7, 1967, in the names of James J. Grimm and Robert J. Valihura and entitled "Marking Tag and Method of Making an Attaching the Same."

SUMMARY

The invention relates to a machine for assembling and securing marking tags to an article. Facilities are provided for positioning a backup layer of sheet material along the edge of the article to be marked with portions of the material lying on each side of the article. The threadlike securing element is then passed through the article and the ends of the securing element are laid parallel to the article on at least one side of the article so that at least one end thereof extends generally toward an edge of the article. Facilities are provided for then superposing and adhering a cover layer of sheet material over the backup layer on each side of the article to enclose and anchor the ends of the securing element therebetween.

In the preferred embodiment of the machine, the threadlike securing element also passes through the backup layer on each side of the article prior to being laid parallel to the article. The backup and cover layers are preferably cut from a spool having an indeterminate supply thereof so that the feeding and handling of the layers is simplified. Also, it is desirable that the cover layer be provided with a surface having a heat sealable adhesive thereon for adhering the cover and backup layers together to anchor the securing element therebetween. Also, in the preferred form the securing element is a fine wire and the backup layer is made of a "wet-strength" paper so as to be resistant to deterioration during washing or other similar operations.

The backup layer and the cover layer should be joined along the edge of the article. This can be accomplished by either making the backup layers out of one single piece of material which is folded, or by making the cover layers from one piece of material which is folded over the edge of the article.

The tag assembled and attached by the above described machine has the advantage of simplicity since no pins or staples, etc., are required to secure the tag to the article. There is also the very distinct advantage that the force which is applied to the securing element, i.e., the fine wire, is applied against the tearable backup layer and not the article itself. Therefore, the securing element can be made of a high tensile strength wire to prevent inadvertent release since the release of the tag does not depend upon breakage of the securing element, as is common in previously known devices. The marking tag made by the instant machine also has the advantage that once it is removed from the article it is effectively destroyed and cannot be surreptitiously attached to another article, which is useful

when the tag is used as a price tag. Additionally, the tag can be readily assembled with "fly tags" which are frequently used in laundering and dry cleaning operations to indicate special procedures which are to be performed on the particular garment. However, this aspect has not been disclosed in this application and forms no part of this invention.

The marking tags which have used threads in the past normally either required scissors or other type of tool to cut the thread; or the tag was removed by breaking the thread against the fabric to which it was attached. The marking tag assembled by the instant machine requires no tool for the removal and is not damaging to the fabric even though a fine wire is used as a securing element. Use of a fine wire also provides the advantage that its insertion through the fabric results in essentially no damage thereto by reason of its small diameter, although it should be clear that this invention is not limited to the use of a fine wire and includes other equivalent securing elements.

20

DRAWINGS

Other objects, advantages and aspects of the invention will become apparent by reference to the following detailed description and drawings of a specific embodiment thereof, 25 wherein:

FIG. 1 is a schematic exploded view of the preferred embodiment of the marking tag which is assembled and attached by the machine forming the instant invention;

FIG. 2 is a cross-sectional side elevational view of the same tag shown in FIG. 1 as it is being removed from an article;

FIG. 3 is a schematic view of the machine forming the instant invention for assembling and securing a marking tag to an article;

FIG. 4 is a front elevation view of the machine shown in FIG. 3;

FIG. 5 is a plan view of the machine shown in FIGS. 3 and 4;

FIG. 6 is a view partially in section taken along line 6-6 of FIG. 4;

FIG. 7 is the same as the view in FIG. 6 showing the mechanism after an article has been clamped to the platform of the machine;

FIG. 8 is a view partially in section taken along line 8-8 of FIG. 5 showing the mechanism for feeding and folding the backup layer;

FIG. 9 is a plan view of the apparatus shown in FIG. 8;

FIG. 10 is a view partially in section taken along line 10-10 of FIG. 4 showing the linkages for feeding and folding the backup layer;

FIG. 11 is a view partially in section taken along line 11-11 of FIG. 5 showing the printing mechanism;

FIG. 12 is a plan view of the apparatus shown in FIG. 11 with portions removed and showing the linkages for setting the type wheels of the printing mechanism;

FIG. 13 is a side elevation view of the mechanism shown in FIG. 12;

FIG. 14 is a view partially in section taken along line 14-14 of FIG. 4 showing the mechanism for raising the printer mechanism to print indicia on the backup layer;

FIG. 15 is taken on the same view as FIG. 14 and shows the mechanism for feeding the carbon ribbon from one spool to another;

FIG. 16 is a sectional view taken along line 16-16 of FIG. 4 showing the mechanism for inserting the securing element through the article;

FIG. 17 is a front elevation view of the apparatus shown in FIG. 16 showing the mechanism in its lowermost position with the needle extending through the jaws which are holding the article;

FIG. 18 is the same as the view in FIG. 17 showing the apparatus for inserting the securing element through the article in its uppermost position;

FIG. 19 is the same as the view in FIG. 4 with portions removed showing the mechanism for feeding and applying the cover layer;

75

FIG. 20 is the same as the view in FIG. 19 showing the mechanism in its lowered position wherein a cutter mechanism and a heater mechanism have been actuated;

FIG. 21 is the same as the view in FIGS. 19 and 20 with portions removed to show the heater mechanism and the cutter mechanism;

FIG. 22 is the same as the view in FIG. 21 with portions removed showing the mechanism for feeding the cover layer material;

FIG. 23 is a side elevation view taken along line 23-23 of FIG. 4 and showing the mechanisms for controlling the platform and the clamping device as well as the shuttle closing device;

FIG. 24 is a front elevational view of the mechanism shown in FIG. 23;

FIG. 25 is a side elevation view taken along line 25-25 of FIG. 4 showing the drive mechanism for moving the upper and lower cover layer applying mechanisms;

FIG. 26 is a front elevation view of the mechanism shown in FIG. 25;

FIG. 27 is a side elevation view of the mechanisms for moving the securing element applying mechanism and the shuttle;

FIG. 28 is a plan view of the main drive mechanism;

FIG. 29 is a timing diagram showing the sequential operation of the various mechanisms of the machine;

FIGS. 30a and 30b are perspective views of the shuttle mechanism for initially folding the backup layer and then inserting the folded backup layer over the edge of the article;

FIG. 31 is a series of diagrammatic views showing the functional operations which are performed in which;

FIG. 31a is a side elevation view showing the article being clamped;

FIG. 31b is a front elevation view showing the backup layer being folded;

FIG. 31c is a side elevation view showing the folded backup layer being inserted around the article;

FIG. 31d is a side elevation view showing the securing element being gripped after it has been passed through the backup layer and the article therebetween;

FIG. 31e is a side elevation view showing the platform moving away from the shuttle to bend the securing element flat against the surface of the backup layer;

FIG. 31f is a front elevation view showing the cover layers being fed into position over the folded securing element; and

FIG. 31g is a front elevation view showing the cover layers after they have been cut and as they are about to be heated and pressed together against the backup layer and the securing element;

FIGS. 32a, b, c, and d are a series of diagrammatic elevation views from the right side of the machine showing the operation of the ejector mechanism; and

FIG. 33 is an electrical control circuit for controlling the operation of the machine.

DESCRIPTION OF THE INVENTION

In FIGS. 1 and 2 there is shown one example of a marking tag 10 which can be assembled and attached to an article by a machine forming the subject of the instant invention. The tag 10 comprises a backup layer 11 which is folded over the edge of an article 12 which is to be tagged. A securing element 13, such as a fine wire, is passed through and folded parallel to the backup layer 11 and the article 12. Subsequently, a cover layer 14 is adhered to the backup layer 11 and the securing element 13 on each side of the article to secure and anchor the securing element 13 therebetween. Preferably, the cover layers 14-14 are provided with a surface of heat sealable adhesive which when heated securely bonds the various elements together.

Removal of the tag is effected, as shown in FIG. 2, by lifting the backup layer 11 and cover layer 14 on one side of the article so that the securing element 13 tears through the backup layer 11 and is separated therefrom. Subsequent pulling on the backup and cover layer will result in the securing element 13

being withdrawn through the article whereupon the backup and cover layer on the other side may be readily separated from the article 12. It is to be understood that the tag assembled and attached by the subject machine can also comprise a pair of backup layers which are positioned on each side of the article and wherein the cover layer is an integral sheet which is folded over the edge of the article. As should be apparent, it is only necessary that the tag 10 be connected over the edge of the article and this can be accomplished by either folding the backup layer 11 over the edge of the article or by folding the cover layer 14 over the edge of the article.

A very brief description of the overall operation of the machine now follows. Initially, the article 12 is placed on a platform and clamping mechanism 20 (FIG. 3) which is movable in the direction of the arrows. Placing of the garment on the platform 20 initiates one cycle of operation of the machine for assembling and attaching a tag to that article. A discrete piece of backup material 11 is cut and formed by the apparatus designated 80 after which the backup material is rotated and positioned so that the folded edge of the layer extends along the edge of the article 12. As the backup layer is being formed a printing mechanism 200 is actuated to print selected indicia on the backup layer for further identification of the article 12. A securing element applying mechanism 250 then passes the securing element 13 through the backup layer 11 and the article 12 after which the ends of the securing element 13 are bent so that they extend toward the edge of the article 12. The final step in the assembling operation comprises the formation of the covers layers 14-14 by upper and lower cover layer mechanisms designated 350-350. In the preferred embodiment the cover layers 14-14 are adhered to the securing element 13 and the cover layer 11 by a heat sealable adhesive so as to anchor the various elements together.

Platform And Clamping Mechanism 20

Referring now in more detail to the various operating mechanisms and in particular to the platform and clamping mechanism 20 shown in FIGS. 3, 6 and 7, there is provided a platform 21 having an opening 22 for supporting the article 12 during the tag assembling and attaching operation. As the article is positioned on the platform 21, a spring element 23 which projects up into the opening 22 is tripped to actuate one cycle of operation of the machine. Tripping of the spring element 23 causes energization of a solenoid 24 (FIGS. 3 and 28) which through its armature 26 is effective to engage a one way, one revolution spring wound clutch 27 for one cycle of operation. The clutch 27 then connects the power train comprising a continuously operating motor 28, timing belt pulley 29, a timing belt 31, a bushing 32, and a second timing belt pulley 33. The pulley 33 is effective to rotate a cam shaft 34 which when connected with the clutch 27 drives the various cams which will be described in more detail hereinafter. The cam shaft 34 is supported at either end in bearing bracket assemblies 35-35.

Tripping of the spring 23 also energizes a solenoid 36 (FIGS. 3 and 23) which controls the position of a pair of clamp arms 37-37. Energization of the solenoid 36 causes the solenoid armature 38 to advance in the direction of the arrow (FIG. 23) pivoting a lever 39 around a pivot point 40 to tension a spring 41 connected to the ends of a clamp arm support 42. The support 42 is bifurcated to form two clamp arm support levers 43-43 which are pivoted at their end on pins 44-44 supported in the sidewall of the platform 21 (FIGS. 6 and 7).

The clamp arms 37-37 are generally L-shaped and the bottom end of each arm has a pin 46 passing therethrough which is free to slide in a generally vertical slot 47 formed in the side 70 of spring housings 48-48. As the clamp arms 37-37 are lowered to grip an article 12, springs 49-49 are compressed in each of the spring housings 48-48 to provide a resilient, and yet firm, gripping of the article by the arms 37-37. Upon the completion of one cycle of operation and the subsequent deenergization of the solenoid 36, the clamp arms 37-37 are

returned to their upper position by a tension spring 51 (FIG. 23) which is connected between the lever 39 and a platform actuating lever 52.

After the article has been clamped on the platform 21 by the clamp arms 37-37, the platform 21 is moved inwardly into alignment with various other mechanisms for assembling the marking tag (FIGS. 6 and 7). This inward movement is accomplished by the platform actuating lever 52 (FIG. 23) which is biased inwardly by a tension spring 53 connected between the lever 52 and a screw 54 attached to the frame of the machine. At the beginning of a cycle, the platform 21 is positioned in its outward position by a cam 56 which engages the cam follower 57 connected to the lever 52. After the commencement of a cycle, the cam 56 is rotated to a low point on the cam permitting the spring 53 to urge the lever 52 in a counterclockwise direction as shown in FIG. 23. The upper part of the lever 52 is provided with a pin 58 which rides in a slot 59 in the clamp arm support 42.

The platform 21 is provided with two inwardly directed pins 61-61 (FIG. 6) on each side thereof which are positioned in vertical slots 62-62 in each of the clamp arm support levers 43-43. The rearward and subsequent forward movement of platform 21 and the associated clamp arms 37-37 is guided for horizontal, rectilinear motion by a pair of platform guide brackets (only one shown) 63 having horizontal slots 64 in which the pins 61-61 ride. The rearward portion of the guide brackets 63-63 is rigidly connected to the frame of the machine by screws 66-66, shown in FIG. 3. In its most rearward position, the platform aligns the article 12 with the securing element applying mechanism 250. At a later stage in the cycle, the platform 21 is moved forward to an intermediate position in which is in alignment with the cover layer applying mechanisms 350-350 by another raised portion of the cam 56. In the final stages of the cycle the platform 21 is moved completely forward to its starting position as shown in FIG. 6, by the same cam 56.

Base Tape Forming Apparatus 80

As soon as the spring element 23 is tripped and the cam shaft 34 commences one cycle of rotation, the formation of a discrete strip of folded backup layer is commenced by the mechanism 80. As shown in FIGS. 3, 8 and 9, an indeterminate length of base tape 11 is wound on a spool 81 supported on a shaft 82 positioned on the right side of the machine. The leading end of the backup layer 11 passes through the nip of a feed roller 83 and idler roller 84 for feeding the backup layer through a horizontal guide 86 and into a vertical guide 87 until it strikes a stop 88. The rollers 83 and 84 and the guides 86 and 87 are supported on a bracket 89. The bracket 89 also supports the mechanism designated 91 for folding the backup layer into a generally V-shape between a pair of jaws 92 and 93 supported on a shuttle 94. The jaws 92 and 93 are normally biased in the open position by a torsion spring 96 (FIG. 30a).

The feed roller 83 is supported on a shaft 101 (FIGS. 8 and 10) having a gear 102 positioned on the other end thereof. The gear 102 is in mesh with a gear segment 103 which is pivotally mounted at 104, and has a cam follower 106 on the other end thereof. The cam follower 106 follows the surface of a cam 107 mounted on a cam shaft 108 connected with the cam shaft 34 by a pair of bevel gears 109 and 111 (FIG. 28). The cam shaft 108 is supported at either end in bearing bracket assemblies 112 and 113. Rotation of the cam 107 causes the gear segment 103 to move in a counterclockwise direction as indicated by the arrow in FIG. 11 to rotate the drive wheel 83 a predetermined amount so as to feed a fixed amount of backup layer material from the spool 81 on each cycle of operation. The gear 102 is provided with a one way clutch (not shown) so that the feed roller 83 does not rotate as the gear segment 103 is returned by a tension spring 114 (FIG. 10) secured to the frame of the machine.

After each feeding cycle of the backup layer 11, a stationary blade 121 (FIGS. 8 and 9) and a pivotally mounted blade 122 are effective to cut the base tape leaving a discrete strip of backup layer material extending upwardly in the guide way 87 against the stop 88. The blade 122 is pivoted at 123 (FIG. 14) and is connected at the other end to an armature 124 of a solenoid 126. The solenoid 126 is energized at the proper time by a microswitch 127 (FIG. 28) and cam 128 mounted on the cam shaft 34. As should be apparent, the armature 124 is drawn into the solenoid 126 upon energization (FIG. 14) raising the cutting end of the blade 122 so that the backup layer 11 is severed between the blades 121 and 122. Upon deenergization of the solenoid 126, a tension spring 129 returns the cutting end of the blade 122 to its lower position for permitting the leading edge of the now severed backup layer to be fed on the next cycle of operation.

With the base tape so severed and lying in the vertical passageway 87, it is now possible to fold the base tape into a generally V-shaped configuration between the jaws 92 and 93 of the shuttle 94. This is accomplished by urging a former punch 131 (FIG. 8) to the left through an opening 132 in the sidewall of the vertical guide 87 into the open jaws 92 and 93. The former punch 131 has an arcuately shaped leading surface 133 with a pointed rod 134 secured thereto. As the former punch 131 moves to the left (FIG. 8) the backup layer 11 is withdrawn from the upper and lower portions of the vertical guide 87 until it is pressed between the jaws 92 and 93. The backup layer 11 has enough natural resiliency so that when the former punch 131 is retracted the backup layer 11 remains between the jaws 92 and 93.

The former punch 131 is secured to a sliding support 136 having pins 137-137 extending laterally into slots 138 in the bracket 89 for horizontal movement back and forth. The support 136 also includes a drive pin 141 which is positioned between the furcations of a forked lever 142 (FIGS. 8 and 11). The lever 142 is generally U-shaped (FIG. 10,) and is pivoted at points 143-144. Just below the pivot point 144, the lever 142 is connected to a driving lever 146 by a pin 147. The lever 146 is pivoted at 148 and has a cam follower 149 at the other end thereof for following the surface of a cam 150 mounted on the cam shaft 108. The cam 150 and a tension spring (not shown) cause the lever 142 to rock back and forth at the proper time in the assembling sequence to push the former punch 131 into the arms 92 and 93 of the shuttle 94.

After the former punch 131 has placed the backup layer 11 in the jaws 92 and 93 of the shuttle 94, it is desired to rotate the backup layer through 90° and to advance the backup layer forward a certain distance so that the folded edge of the layer is adjacent to the edge of the article 12. In FIG. 30a the shuttle 94 is shown in its position as it receives the backup layer 11; and in FIG. 30b the shuttle 94 is shown after it has been rotated 90° and advanced forwardly toward the edge of the article 12.

The shuttle 94 includes a shuttle frame 151 having a drive pin 152 (FIG. 8) extending upwardly therefrom. The frame 151 also acts as the support for a pin 153 on which the jaws 92 and 93 are pivotally mounted. The drive pin 152 includes an upwardly extending arm 154 having a cam follower 156 mounted on the end thereof. The cam follower 156 rides in a slot 157 which is cut in a tracking cam 158 secured to the frame of the machine by a bracket 159. The drive pin 152 is carried by the upper fork 161 of a bifurcated shuttle bracket 162. The bracket 162 supports a pin 163 which is movable laterally, forward and backward, by a lever 164 (FIG. 27). The lever 164 (FIG. 25) is pivotally mounted on a pin 166 and is provided with a cam follower 167 which follows the surface of a cam 168 mounted on the cam shaft 34. The cam 168 is shaped to pivot the lever 164 in the clockwise direction (FIG. 27) so as to move the shuttle bracket 162 forward at the proper time in the operational sequence.

The lower portion of the shuttle frame 151 is provided with a shaft 171 (FIG. 8) which rides in a slot 172 (FIGS. 30a and 30b) provided in a lower tracking plate 173 secured to the frame

of the machine. The drive pin 152 rides in a similar slot 172' in an upper tracking plate 173'. The slots 172 and 172' ensure the rectilinear movement of shuttle 94 in both the forward and reverse directions.

The shape of the slot 157 in the tracking cam 158 is such that the cam follower 156 rotates the shuttle 94 through 90° as the shuttle 94 is moved forwardly by the lever 164. This motion is shown most clearly in FIG. 30b.

At this point it is desired to close the jaws 92 and 93 tightly around the backup layer 11 so that the folded edge lies adjacent to the edge of the article 12. The jaws 92 and 93 are provided with bosses 176 and 177, respectively, which are in alignment with corresponding pivotable arms 178 and 179 (FIGS. 6 and 7) provided for closing the jaws 92 and 93. The arms 178 and 179 are pivotally mounted at 181, and are biased together by a tension spring 182. A cam 183 maintains the arms 178 and 179 in their open position until such time as the shuttle 94 is rotated 90° over the edge of the article 12. At this time the jaws are closed by rotation of the cam 183 (FIG. 7) so that the ends of the arms 178 and 179 engage the bosses 176 and 177 to close the jaws.

The rotation of the cam 183 is effected by rotating its support shaft 184 which is connected by an L-shaped lever 186 (FIGS. 3 and 23) to the end of another lever 187. The lever 187 is pivotally mounted at 188 and the other end of the lever is provided with a cam follower 189 which is in engagement with a cam 191 mounted on the cam shaft 34. The cam 191 pivots the lever 187 to rotate the lever 186, which turns the cam 183 approximately 90° to permit the closing of the jaws 178 and 179 by the tension spring 182. Subsequently, the lever 187 is urged in the opposite direction by a tension spring 192 (FIG. 3) to again open the arms 178 and 179 to permit the retraction of the shuttle 94. As the shuttle 94 returns along the tracking cam 158 and the upper and lower tracking plates 172 and 172', the shuttle 94 is rotated 90° in the reverse direction so that it is ready to receive the next backup layer from the forming punch 131 on the following cycle of operation.

When the jaws 92 and 93 are opened, the bosses 176 and 177 engage the shuttle frame 151 to limit their movement. The jaws 92 and 93 can also be provided with tangs 193-193 to hold the backup layer therein as it is rotated.

Referring to FIGS. 32a-d there is shown an ejector mechanism, designated generally 194. The mechanism includes an upstanding ejector bar 195 which is positioned against the folded edge of the backup layer 11 after the jaws 92 and 93 have closed therearound (FIG. 32b). The ejector bar 195 is mounted on a support 196 which is slidable fore and aft with respect to the lower jaw 93. A tension spring 197 connected between an extension of the lower jaw 92 and the support 196 normally urges the support 196 into the rearward position. The forward end of the support 196 includes an upturned hook 198 which engages with a projection 199 on the platform 21 when the jaws 92 and 93 are closed in FIG. 32b. As the platform 21 is moved outwardly (to the left in FIG. 32c) by the cam 56, the support 196 and the ejector bar 195 are pulled therewith so as to push the backup layer 11 and the garment 12 therewith. Subsequently, as the jaws 92 and 93 are opened, the hook 198 disengages from the projection 199 permitting the support 196 and the ejector bar 195 to return under the influence of the spring 197.

Printer Mechanism 200

Referring to FIGS. 11-15 there is shown the printing mechanism 200 for placing the desired indicia on the base tape for later identification of the article 12. The printing cycle should take place while the backup layer 11 is positioned in the horizontal guide way 86 and before the feed roller 83 advances the backup layer into the vertical guide way 87.

In FIG. 14 there is shown an opening 201 in the bottom of the horizontal guide way 86 through which a plurality of printing wheels 202-202 can be raised to strike against the bottom

surface of the backup layer 11. The printing wheels 202 are provided with any suitable indicia such as numerals or letters which can be aligned with the opening 201 by the manipulation of a plurality of handles 203-203, there being one such handle for each of the printer wheels 202. The handles 203-203 (FIGS. 12 and 13) are each connected to their respective printer wheels 202-202 by bent levers 204-204 having racks 206-206 positioned on the end thereof. The levers are bent in graduated manner to occupy the least amount of space. The racks 206-206 are in mesh with respective gears 207-207 which in turn are in mesh with gears 208-208 one of which is associated with each of the printer wheels 202-202. The printer wheels 202-202 and the gears 208-208 are mounted on a shaft 209 supported on a frame 210. By raising or lowering the levers 203-203 each of the type wheels 202-202 can thereby be set. The wheels are held in this position by spring detents 211-211 (FIG. 13).

In FIG. 11 there are shown two spools 212 and 213 on which is wound a carbon ribbon 214. The ribbon 214 is fed from the spool 212 up along the side of the frame 210 for the printer, across the face of the uppermost portion of the type wheels 202-202 and then down the other side of the frame 210 to be rewound on the spool 213. The carbon ribbon 214 is only shown as it leaves and returns to the spools 212 and 213, and the remainder has not been shown for simplicity.

The printing of the proper indicia against the backup lever 11 is effected by raising the type wheels 202-202 so that the wheels strike the base tape. The force of the printer wheels 202-202 is partially absorbed by a hard rubber pad 221 (FIG. 14) which is provided in the upper part of the guide way 86. The type wheels 202 are raised by a generally L-shaped, forked lever 222 which is pivoted on a pin 223. The forks of the lever 222 are positioned under a lifting pin 224 which is connected to the frame 210. An outer frame 226 is provided with slotted guide ways 228-228 on each side which receive pins 229-229 for insuring the vertical movement of the frame 210 and its associated printer wheels 202-202. At the appropriate time in the cycle, a solenoid 231 is energized (FIG. 14) thereby drawing its armature 232 and the associated linkage 233 to the right to cause pivoting of the lever 222 in a clockwise direction. The solenoid 231 is energized by a cam 234 (FIG. 28) which closes a microswitch 236 electrically connected to the solenoid 231. A spring 237 (FIG. 14) is provided between the linkage 233 and the upper portion of the lever 222 to cushion the movement of the relative parts. After the solenoid 231 is deenergized the type wheels 202-202 and the lever 222 return to their original position by gravity.

As shown in FIGS. 11 and 15 the advancement of the carbon ribbon 214 is effected by a ratchet 241 which is mounted on the lower end of the frame 210. A pawl 242 is pivoted at 243 and biased into engagement with the teeth on the ratchet 241 by a spring 244. After each printing cycle as the frame 210 is descending, the pawl 242 engages the ratchet 241 causing it to rotate thereby rotating the spools 212 and 213 to advance the carbon ribbon 214.

Wire Inserting Mechanism 250

After the shuttle 94 and the folded backup layer 11 have been rotated so that the backup layer overlies the edge of the article 12, and after the arms 92 and 93 have been tightly closed around the backup layer, it is desired to pass the securing element 13 through both sides of the backup layer and the article 12 therebetween. Referring to FIGS. 16-18, this is accomplished by passing a hollow needle 251 downwardly through openings 252 and 253 in the jaws of 92 and 93, and severing the wire by cutting mechanism 254 while the leading end of the wire is gripped by a gripping device 256. The cutting mechanism 254, of course, does not operate until the needle 251 has been retracted thereabove.

A spool 261 is mounted for rotation on a shaft 262 positioned inside a cartridge 263. The spool has an indeterminate length of securing element, such as wire, thereon for providing

discrete lengths of the wire for each cycle. The rear of the cartridge 263 is provided with pins 264-264 which ride in an elongated slot 265 of a forked drive lever 266. Turning of the lever 266 in the direction of the arrow as shown in FIG. 16 results in lowering the cartridge 263 on a pair of sleeves 264-267 which ride on vertical guide posts 268-268 secured to the frame of the machine. Also connected to the frame of the machine is a compression spring 269 which surrounds a vertical shaft 271. The bottom of the shaft 271 is connected to a cam 272 which rides underneath the housing of the cartridge 263 as the cartridge is moved downwardly. At the top of the shaft 271 is a nut 273 so that as the cam 272 is lowered the spring 269 is compressed. The force stored in the spring 269 is sufficient in the latter part of the cycle to return the cartridge 263 and its associated hollow needle 251 to the upper position.

In order to feed wire relative to the tip of the hollow needle 251, there is provided an idler roller 276 mounted for rotation on a shaft 277, and a feed roller 278 mounted on a drive shaft 279. The wire 13 is fed from the spool 261 downwardly through a passageway 281 in the cartridge housing and into the nip of the rollers 276 and 278. From there the wire continues downwardly through a passageway 282 and on through the hollow needle 251.

It should be apparent that during the penetration of the needle 251 with the two sides of the backup layer 11 and the article 12 it is desirable that the wire 13 be entirely enclosed within the needle 251. Subsequently, it is desired to feed the wire 13 relative to the end of the needle 251 into the gripping device 256 so that as the needle 251 is then withdrawn the wire 13 is paid off the spool 261 in the desired amount. This feeding of the wire 13 relative to the needle 251 is accomplished by a drive wheel 283 having an eccentrically mounted pin 284 protruding therefrom. The drive wheel 283 is mounted coaxially with the feed roller 278 so that rotation of the drive wheel causes a similar degree of rotation of the feed roller 278. For this purpose an activator or camming surface 286 is appropriately positioned so as to strike the pin 284 as the cartridge 263 moves downwardly on the guide post 268-268. The pin 284 strikes the surface 286 (FIG. 17) prior to the completion of the downward movement of the cartridge 263 so as to rotate the drive wheel 283 and its associated feed roller 278.

The gripping device 256 is positioned so that the wire 13 which is fed out of the end of the needle 251 is positioned between a movable jaw 287 and a fixed jaw 288. The movable jaw 287 is mounted on a shaft 289 which forms the armature of a solenoid 291. At the proper time in the sequence, the solenoid 291 is energized by the closure of a microswitch 292 controlled by a cam 293 mounted on the cam shaft 34 (FIG. 28). Energization of the solenoid 291 causes the armature 289 and the jaw 287 to move to the right (FIG. 17) thus gripping the leading end of the wire 13 between the two jaws.

After the leading end of the wire 13 has been gripped, the drive lever 266 permits the compression spring 269 to commence raising the cartridge 263 and the needle 251. After the needle 251 has passed through the cutting mechanism 254, it is desired to sever the wire 13 into a discrete length. The cutting mechanism 254 comprises a stationary cutting blade 294 and a movable blade 295 positioned therebelow. The blade 295 is held against the blade 294 by a spring 296. The blades 294 and 295 and the spring 296 are all provided with apertures (unnumbered) through which the wire 13 passes. The movable blade 295 is urged in the direction of the arrow (FIG. 18) to sever in the wire by a shearing action between rounded surfaces 297 and 298 of the stationary and the movable blades, respectively.

The movable blade 295 is actuated by the energization of a solenoid 301 (FIGS. 23 and 24) acting through its armature 302 and connecting link 303 and a lever 304 pivoted on a pin 306. The end of the movable blade 295 is secured between the furcations 307-307 of the forked end of the lever 304 by a pin 308. The solenoid 301 is energized at the proper time by a

microswitch 311 (FIG. 28) which is closed by its associated cam 312 mounted on the cam shaft 34. The return of the cutting blade 295 to a position where the openings in the stationary and movable blades 294 and 295 are aligned is effected by a tension spring 313 which is mounted between the upper end of the lever 304 and an L-shaped bracket 314 extending from the frame.

In order that there be no wire 13 extending from the tip of the needle 251 at the end of the cycle, it is necessary to feed the wire 13 upwardly within the passageway 281 by the rollers 276 and 278. This is accomplished by the pin 284 striking the cam 272 as the cartridge 263 is moving upwardly so as to rotate the drive wheel 283 in the reverse direction. Thus, the feed roller 278 rotates in the clockwise direction (FIG. 18) to withdraw whatever wire might be extended from the tip of the needle 251 in preparation for the next cycle of operation.

The drive lever 266 for lowering the cartridge 263 is generally L-shaped, (FIG. 27) and is pivoted on a pin 316. The other end of the lever 266 has a pin 317 which rides in a slot 318 of a cam link 319. The cam link 319 is pivoted at 321 and includes a cam follower 322 which follows the surface of a cam 323 mounted on the cam shaft 34 (FIG. 28). The lever 266 is returned by a tension spring (not shown) connected to the frame of the machine.

Cover Layer Applying Mechanism 350

In FIG. 3 there is shown the upper and lower cover layer applying mechanisms 350-350 for applying the cover layers 14-14 over the backup layer 11 and the securing element 13. The article 12 at this time is still clamped on the platform 21 which has moved outwardly to an intermediate position where the article 12 is in vertical alignment with the two cover layer applying mechanisms 350-250. The partial movement of the platform 21 outwardly is accomplished by the cam 56 (FIG. 23) acting against the force of the tension spring 53. Since the cover layer applying mechanisms 350-350 are identical except for their different orientation, only the elements and operation of the upper mechanism will be described hereinafter.

Referring to FIGS. 19-22 there is shown the upper cover layer applying mechanism 350 which includes a spool 351 mounted for rotation on a shaft 352 supported on a frame 353 mounted for vertical, rectilinear motion. Extending from the frame 353 is a pair of upper guide pins 354-354 and lower guide pins 355-355. The guide pins 354-354 and 355-355 ride in vertical slot 256-356 (FIG. 3) in guide brackets 357-357 secured to the frame of the machine. The upper pins 354-354 are urged toward the platform 21 and the article 12 supported thereon by a forked lever 358 having bifurcated ends 359-359 which engage the pins 354-354. The mechanism for actuating the forked lever 358 will be discussed hereinafter.

The cover layers 14-14 are preferably made of a foil having a coating of heat sealable adhesive thereon. The cover layers will hereinafter be referred to as foil for exemplary purposes and not by way of limitation.

The foil 14 is fed from the spool 351 over a guide spool 361 and downwardly between an idler roller 362 and a feed roller 363. The foil is then fed through a curved guide 364 into position beneath a pivotally mounted blade 366. After the blade has severed a discrete piece of foil from the indeterminate length thereof, a pivotally mounted heater 367 is moved into engagement with the foil to apply heat and pressure to the foil as it is positioned on top of the backup layer 11 and the securing element 13.

The mechanisms for feeding, cutting and heating the foil 14 will now be described in more detail. The feed roller 363 is mounted on a common shaft with a gear segment 371 which is in mesh with a rack 372 secured to the frame of the machine. A pawl 373 (FIG. 22) is secured to the gear segment, and a ratchet 374 is connected to the feed roller 363. Therefore, as the frame 353 is lowered the drive wheel 363 is rotated to feed the foil 14 between the nip of the rollers 362 and 363. On the

return movement of the frame 353, the gear segment 371 meshes with the rack 372, but imparts no rotary motion to feed roll 363 by reason of the ratchet and pawl connection. A spring 376 can also be provided for urging the rollers 362 and 363 together.

The blade 366 is mounted on a pivot 376 which is supported in an arched frame 377. A leaf spring 378 (FIGS. 19 and 20) urges the upper end of the blade outwardly from the machine so as to maintain the cutting surface of the blade above the foil 14 which is being fed through the guide 364. In order to pivot the blade 366 downwardly across the path of the foil 14, there is provided a camming lever 379 which is carried on the frame 353 by a pair of screws 381-381. Mounted at the lower end of the camming lever 379 is an L-shaped bracket 382 having a roller cam 383 secured at the end thereof. The roller cam 383 is aligned with the blade 366 so that vertical movement of the blade 366 downwardly with respect to the roller 383 will result in a pivoting motion of the blade 366 across the path of the foil 14. The relative movement of the frame 353 and the camming lever 379 is accomplished by providing a first limit stop 386 which is positioned in the path of a flange 387 of the camming lever 379. Initially, as the frame 353 is moved downwardly, the camming lever 379 is carried therewith. When the flange 387 strikes the stop 386 the roller cam 383 moves upwardly relative to the blade 366 and the frame 353 to which it is secured, as shown in FIG. 18. This causes the blade 366 to pivot and sever a predetermined length of the foil from the strip.

In order to pivot the heater 367 against the now severed piece of foil 14 the camming lever 379 is provided with an extension 388 having a slot 389. Positioned in the slot 389 is a pin 391 which is mounted on the lower end of the heater 367 (FIG. 21). As the flange 387 strikes the limit stop 386 the extension 388 moves the pin 391 upwardly relative to the frame 353 thereby causing the heater 367 to pivot in a clockwise direction, as shown by the arrow in FIG. 21. The other end of the heater 367 includes an iron 392 which is heated inductively by an electric heater 393. The iron 392 pivots clockwise (FIG. 21) and at the same time the heater associated with the lower foil applying mechanism 350 pivots clockwise (FIG. 31g) so that the foil 14, the securing element 13, the backup layer 11, and the article 12 are all gripped therebetween in the opening 22 of the platform 21. The two irons 392 apply heat and pressure to the thus assembled elements to cause the heat sealable adhesive on the inner side of the discrete pieces of foil 14 to bond all the elements together. It is desirable that a heat shield 394 be provided so as to shield the foil 14 and the other mechanisms from the high temperatures generated by the heater 393.

When the frame 353 is subsequently moved away from the platform 21, the camming lever 379 moves therewith until the flange 387 strikes a second limit stop 395. The frame 353 moves upwardly somewhat further thus causing relative movement between the camming lever 379, the blade 366 and the heater 367 thereby allowing the blade 366 to return to its original position under the urging of the spring 378, also the heater 367 pivots in a counterclockwise direction into its position shown in FIG. 21. Thus, the foil applying mechanism 350 is prepared for the next cycle of operation.

The mechanism for moving the forked lever 358 and the corresponding forked lever 358' for the lower foil applying mechanism 350 is shown in FIG. 25. A cam 396 mounted on the cam shaft 34 controls the position of a cam follower 397 secured to a cam link 398. The cam link is pivoted at 399 and has a forked end 401 in which rides a pin 402 secured to the end of the lever 358. The lever 358 is pivoted at 403, so that counterclockwise movement of the cam link 398 results in lowering the bifurcated end 359 of the lever 358 so as to lower the guide pins 354-354.

An intermediate link 404, which is pivotally mounted at 406, is controlled by a pin 407 which passes through openings in both the link 404 and the cam link 398. The lower end of the intermediate link 404 is provided with a pin 408 which is

connected to the upper end 409 of the lever 358'. The lever 358' is pivoted at 411 and includes a bifurcated end 359' similar to the upper lever 358. Thus, as the cam link 398 is pivoted in a counterclockwise direction the intermediate link 5 404 is urged in a clockwise direction moving the end 409 of the lever 358' in a counterclockwise direction to raise the bifurcated end 359'. Therefore, as the cam 396 rotates through one cycle of operation, the upper lever 358 is lowered and the lower lever 358' is raised so as to bring the foil applying mechanisms 350-350 together on either side of the platform 21.

Operation

15 One complete cycle of the operation of the subject machine for assembling and attaching a marking tag to an article 12 will now be described as shown in the timing diagram (FIG. 29) and the schematic illustrations in FIGS. 31a-31g. Initially, the article 12 is positioned on the platform 21 over the opening 22. This trips the spring element 23 which initiates one cycle of the cam shaft 34 by engaging the clutch 27 to transmit the rotation of the motor 28. Tripping of the spring element 23 also energizes the solenoid 36 which pivots the lever 39 and the clamp arm support levers 43-43 to tightly engage the clamp arms 37-37 against the article 12 (FIG. 31a).

With the article 12 so gripped, the cam 56 urges the lever 52 rearwardly so as to move the platform 21 and its associated clamp arms 37-37 rearwardly to its innermost position in which it is in vertical alignment with the securing element applying mechanism 250.

Previously, the operator of the machine has positioned the handles 203-203 according to the desired indicia which are to be printed on the tag. The solenoid 231 is then energized by the closing of the microswitch 236 by the cam 234 to raise the printing mechanism 200 so that the type wheel 202-202 print the proper identification on the bottom side of the backup material 11 (FIG. 31b).

Subsequent to the printing operation, the backup layer 40 feeding cam 107 (FIG. 10) pivots the gear segment 103 to rotate the gear 102 and its associated feed roller 83. This causes feeding of a predetermined amount of the backup layer material from the spool 81 into the vertical guide way 87 (FIGS. 8 and 31b).

45 Shortly after the backup layer 11 has been fed into the vertical guide way 87, the cam 128 closes the microswitch 127 thereby energizing the solenoid 126 (FIG. 14) to raise the blade 122 against the stationary blade 121 to sever the backup layer. This leaves a discrete strip of material positioned in the vertical guide way 87 ready for being folded into the arms 92 and 93 of the shuttle 94.

The former punch 131 is moved between the jaws 92 and 93 to fold the severed backup layer at this time. This is accomplished by the cam 150 rocking the lever 146 (FIG. 10) to urge the lever 142 (FIG. 8) to the left thus moving the former punch 131 between the jaws 92 and 93.

With the backup layer so positioned between the jaws 92 and 93, the shuttle cam 168 actuates the lever 164 driving the shuttle bracket 162 forward. This causes the shuttle 94 to rotate 90° (FIGS. 30a, and b) and advance to a position where the folded backup layer 11 overlies the article 12 (FIG. 31c).

With the shuttle 94 so positioned, the shuttle closing cam 191 actuates the lever 187 (FIG. 3) and the lever 186 to rotate the cam 183 (FIGS. 6 and 7) holding the arms 178 and 179 apart. The arms 178 and 179 engage the bosses, 176 and 177 to close the jaws 92 and 93 tightly around the backup layer 11 and the article 12 (FIG. d).

With the jaws 92 and 93 so clamped, the hollow needle 251 is lowered to penetrate the backup layer and the article 12 (FIG. 31d). This is accomplished by the wire insert cam 323 pivoting the lever 266 so as to lower the cartridge 263 and the associated spool of wire 261. After the needle 251 has penetrated the backup layer 11 and the article 12 (FIGS. 16-75 18), the feed roller 278 advances the wire 13 relative to the

end of the needle 251 so that the wire lies between the jaws 287 and 288 of the gripping device 256. The cartridge 263 and the needle 251 are then raised under the urging of the compression spring 269 while playing off the wire 13. After the needle 251 has been withdrawn above the cutting mechanism 254, the wire cutting cam 312 closes the microswitch 311 to energize the solenoid 301 (FIGS. 23 and 24). This moves the blade 295 relative to the stationary blade 294 to sever the wire into a discrete piece. Upon continued upward movement of the cartridge 263 the pin 284 strikes the cam 272 thereby rotating the feed roller 278 in a reverse direction to retract the leading end of the wire 13 into the end of the needle 251. The solenoid 291 is now deenergized and the movable jaw 287 moves away from the stationary jaw 288 to free the leading end of the wire 13.

The platform 21 is then moved outwardly to an intermediate position by the cam 56 and the lever 52 (FIG. 23) to a position wherein the backup layer 11 is aligned vertically with the upper and lower cover layer applying mechanisms 350-350. Movement of the platform forwardly (FIG. 31e) causes the ejector pin 195 to push the backup layer 11 out of the jaws 92 and 93. As this is happening the wire 13, which is threaded through the openings 252 and 253 in the jaws 92 and 93, if folded or bent to so that it lies flat against the horizontal surfaces of the backup layer 11. The tag is now in position to receive the cover layers 14-14 from the cover layer applying mechanisms 350-350.

At the same time that the platform 21 is moving to its intermediate position, the cover tape applying mechanisms 350-350 are moving toward the article 12 positioned on the platform 21. The movement of the mechanisms 350-350 toward one another is controlled by the cam 396 acting on the cam link 398 (FIG. 25), intermediate link 404 and the levers 358 and 358'. This moves the frames 353-353 toward each other so as to advance the foil 14 between the idler roller 362 (FIG. 19) and feed roller 363 (FIG. 31f). The blade 366 is pivoted by the roller cam 383 connected to the camming lever 379 to cut the foil 14 and subsequently the iron 392 (FIG. 31g) is pivoted to press the severed foil 14 against the backup layer 11, wire 13 and the article. The same action is likewise occurring on the other side by the oppositely disposed iron 392' of the lower foil applying mechanism 350. The heat from the irons 392 and 392' causes the heat sealable adhesive on the inner side of the foil cover layers 14 to bond and anchor the various elements together. After this operation has been performed, the foil applying mechanisms 350-350 are moved apart to their respective upper and lower positions. During this time the blade 366 pivots back to its original position as does the heater 367.

During the cutting and heating steps, the shuttle jaws 92 and 93 have again been opened by rotation of the cam 191, and the shuttle 94 has been rotated 90° to its position in alignment with the former punch 131 by the lever 164.

As the mechanism 350-350 are being moved away from the platform 21, the platform 21 is moved to its outermost position by the cam 56 acting on the lever 52 (FIG. 23).

When the cycle is completed, the solenoid 24 is deenergized thereby disengaging the clutch 27 from the main cam shaft 34. The deenergization of the solenoid 24 results in the deenergization of the solenoid 36 thereby permitting the springs 41 and 51 (FIG. 23) to raise the clamp arms 37-37. This permits withdrawal of the tagged article 12 and places the machine in condition for the next cycle of operation.

The electrical control circuit for operation of the machine is shown in FIG. 33. A supply of alternating current is provided across points 421-422. A switch 423 is manually closed to supply current to the drive motor 28. The motor runs constantly while the switch 423 is closed. Another switch 424 is manually closed to operate the foil heaters 393-393'. The switches 426-426' open their respective circuits when the heaters reach a predetermined temperature.

The supply of backup material 11 from the spool 81 is monitored in two respects. First, approximately one label length

(1 1/4") is manually advanced into the horizontal guide 86 of the backup material cutting and forming mechanism 80 thereby closing a switch 427 (as shown in the drawing). This opens the circuit to a warning light 428 thereby extinguishing the light and indicating the presence of advanced backup material.

5 A second warning light 429 indicates the presence or absence of backup material on the spool 81. When the supply 10 gets too low, a switch 431 closes the circuit to the warning 15 light 429. At other times the switch 429 is positioned as shown in FIG. 33.

The switches 427 and 431 are each in another circuit which 20 controls the overall operation of the machine via control of the clutch 27. When a garment is placed on the platform 21 the switch 23 is closed. If switches 427 and 431 are closed (as 25 shown) a circuit is completed to a time delay circuit, indicated generally as 432, which includes a relay 433. Energization of the relay 433 closes two sets of contacts 434 and 436. The contact 434 completes a circuit to the solenoid 24 controlling the clutch 27 to start one cycle of operation. At the same time the contact 436 completes a circuit to the solenoid 36 controlling the clamping of the garment to the platform 21. After a short interval of time, the time delay circuit 432, in a well-known manner, opens the circuit to deenergize the relay 433. However, in the meantime the clutch 27 has commenced one cycle of operation, thereby rotating a cam 437. The cam 437 closes a switch 438 to bypass the contact 436 and maintain energization of the solenoid 36. Alternatively, the switch 438 30 can be closed by one of the other cams, such as the platform cam 56. In this case it is desirable to add a link between the cam 56 and the switch 23 for opening the switch 23 at the end of each cycle.

Engagement of the clutch 27 causes rotation of the cams 35 312, 293, 234, and 128 thereby closing their respective switches 311, 292, 236, and 127 at the appropriate time in the operating cycle. In turn, circuits are completed to the wire cut solenoid 301, the wire grip solenoid 291, the print solenoid 231, and the backup material cut solenoid 126, respectively.

40 At the end of one cycle the clutch 27 is disengaged, the garment clamps 37 are released, and the garment, now tagged, may be removed from the platform 21. The machine is then ready for another cycle of operation.

It is to be understood that in the formation of the marking tag disclosed in FIGS. 1 and 2 it is desirable that the backup layer and cover layer on the upper side of the article be joined with the backup and cover layer on the bottom side of the article across the edge of the article. This insures that the tag is held closely to the article until such time as it is removed. In the embodiment shown in FIGS. 1 and 2, this is accomplished by forming the backup layers from a single folded sheet of backup layer material and then adhering two separate cover layers, one to the upper and one to the lower surface of the backup layer. It should be readily apparent that the same

50 result can be accomplished by forming the backup layer from two separate strips of material and using one single sheet of folded material for the cover layer. It is also within the scope of this invention to modify the machine so that the backup layers and the cover layers are both formed from two separate sheets, neither of which is folded across the edge of the article. In assembling such a tag with the subject machine, the connection of the upper backup and cover layers with the lower backup and covers layers along the edge of the article can be

55 accomplished by adhering the upper and lower layers together with an adhesive such as a heat sealable adhesive discussed above. It would also be possible to join the upper layers with the lower layers along the edge of the article with a securing means such as a pin, staple, or other such device. Of course, 60 this latter embodiment is not as desirable as the tag disclosed in FIGS. 1 and 2 since it requires an additional step and an additional securing device. However, the advantages of using a securing element, such as a wire, which is sandwiched between upper cover and backup layers and lower cover and

65 backup layers is still preserved in this type of a tag and is 70 75

within the contemplation of the subject invention. Such a tag would be removed from the article in the same manner as the embodiment shown in FIGS. 1 and 2, namely by raising the upper (or lower) backup and cover layers so that the securing element tears through the backup layer to free the end of the the securing element which can then be withdrawn from the article by continued pulling. The securing element does not tear against the article itself, and, consequently, a strong securing element made of a wire, for example, can be used.

It is to be understood that the invention is not limited to the particular embodiments and features described and shown, but that it comprises any modifications and equivalents within the scope of the appended claims.

We claim:

1. An apparatus for assembling and securing marking tags to an article, which comprises:

means for positioning a backup layer of sheet material along the edge of the article and on each side of the article;

means for passing a threadlike securing element through the article;

means for laying the securing element parallel to the article on at least one side of the article so that at least one end thereof extends generally toward an edge of the article; and

means for superposing and adhering a cover layer of sheet material over the backup layer on each side of the article to enclose an anchor the ends of the securing element therebetween and join the cover and backup layers along the edge of the article

2. An apparatus for assembling and securing marking tags to an article, which comprises:

means for positioning a folded backup layer of sheet material over the edge of the article with portions of the layer lying on each side of the article;

means for passing a threadlike securing element through the article;

means for laying the securing element parallel to the article on at least one side of the article so that at least one end thereof extends generally toward an edge of the article; and

means for superposing and adhering a cover layer of sheet material over the backup layer on each side of the article to enclose and anchor the ends of the securing element therebetween.

3. Apparatus as recited in claim 2 wherein said means for passing the threadlike securing element through the article also passes the threadlike element through the backup layer.

4. Apparatus as recited in claim 3 wherein said means for positioning the folded backup layer of sheet material comprises:

means for cutting a discrete piece of backup layer material from an indefinite length of the same;

means for feeding a predetermined length of the backup material to said cutting means;

means for folding said discrete pieces of material; and

means for moving said folded piece of backup material from the cutting and folding location to the article with the fold of the backup material positioned along the edge of the article.

5. Apparatus as recited in claim 4 wherein said means for folding the discrete piece of backup material includes:

a vertical guide track defining a slot in which said backup material is positioned, said guide member having opposed openings in each side thereof;

a V-shaped shuttle aligned with the openings in said guide track; and

a former punch movable through said openings to fold the backup material into the V of the shuttle.

6. Apparatus as recited in claim 5 wherein said V-shaped shuttle comprises:

a pair of pivoted jaws normally biased apart; and

means for camming said arms together to fold the discrete piece of backup material around the article.

7. Apparatus as recited in claim 5 wherein said former punch includes a curved pusher having a pointed rod affixed to the leading edge thereof for forcing the backup material into the V-shaped shuttle.

8. Apparatus as recited in claim 3 wherein said means for passing the threadlike securing element through the article and the backup layer comprises:

penetrating means for passing the securing element through the article and backup layer;

means for moving the penetrating means and the securing element through the article and backup layer;

means for gripping the leading end of the securing element after it has penetrated the article and backup layer; and

means for withdrawing the penetrating means as the securing element is so gripped.

9. Apparatus as recited in claim 8 which further includes: a spool having an indeterminate length of securing element thereon; and

means for severing the securing element to a predetermined length after the securing element has been passed through the article and the backup layer.

10. Apparatus as recited in claim 8 wherein said penetrating means includes a hollow needle and said securing element is positioned inside the needle.

11. Apparatus as recited in claim 3 wherein said means for passing the threadlike securing element through the article and backup layer comprises:

a hollow needle for piercing the article and backup layer;

30 a spool having an indeterminate length of securing element thereon, said securing element being positioned within the hollow needle;

means for advancing the spool and hollow needle to insert the needle through the article and backup layer, the leading end of said securing element being entirely inside the needle;

means for advancing the securing element relative to the needle after insertion to expose the leading end thereof;

means for gripping and subsequently releasing the leading end of the securing element;

means for retracting the spool and needle while securing element is so gripped to pay off a predetermined length of the securing element; and

means for severing the securing element to provide a discrete length of securing element.

12. Apparatus as recited in claim 11 which further includes means for retracting the leading end of the securing element into the needle after severance and before the next succeeding insertion of the needle through an article and a backup layer.

13. Apparatus as recited in claim 3 which further includes means for printing indicia on said backup tape for identification of said article.

14. Apparatus as recited in claim 3 wherein said means for superposing and adhering a cover layer of sheet material over the backup layer on each side of the article comprises:

means for pressing a discrete strip of cover layer against the threadlike securing element on each side of the backup layer, said cover layers having a surface of heat sealable adhesive adjacent the securing element; and

means for applying heat to said cover layers to enclose and anchor the ends of the securing element therebetween.

15. Apparatus as recited in claim 14 which further includes: upper and lower spools having an indeterminate length of cover layer material thereon;

means for feeding a predetermined amount of cover layer material from each spool; and

means for cutting said predetermined amount from the material on each spool to provide discrete cover layers for each side of the article.

16. Apparatus as recited in claim 3 which further comprises: means for supporting the article to which a tag is to be attached;

upper and lower cartridges, one on either side of the article support means, each having a spool holding indeter-

minate lengths of cover layer material having adhesive on one side thereof;
means for guiding said cartridges for vertical, rectilinear movement;
a pair of feed rollers on each of said cartridges for advancing the cover layer material;
gear means associated with said feed rollers on each of said cartridges for rotating said rollers as the cartridges are moved toward the article to feed a predetermined amount of cover layer material from each of the spools;
cutting means pivotally mounted on each of said cartridges and positioned across the path of the leading edge of each of the lengths of cover layer material for cutting discrete cover layers for each side of the article;
means pivotally mounted on each of said cartridges for applying pressure to the discrete cover layers and the backup layer and securing element positioned therebetween;
means for moving said upper and lower cartridges toward each other and then away from each other; and
cam means associated with each of said cartridges for first pivoting the cutting means to cut discrete upper and lower cover layers and then pivoting said pressure applying means to press the adhesive coated side of said cover layers against the backup layer and the securing element positioned therebetween to form a tag attached to the article.

17. Apparatus as recited in claim 16 wherein said adhesive on the cover layers is heat sealable, and wherein said pressure applying means further includes means for heating the heat sealable adhesive as the cover layers, backup layer and securing element are pressed together on the article.

18. Apparatus as recited in claim 16 wherein said gear means comprises:

a stationary rack mounted adjacent the path of each of the cartridges; and
a gear segment mounted on each of the cartridges which meshes with its respective rack as the cartridges are moved toward each other and the article, said gear segments being connected to one of the feed rollers on each of the cartridges to rotate the same a predetermined amount to feed the cover layer material.

19. Apparatus as recited in claim 18 wherein said gear segments are connected to pawls and said feed rollers are connected to ratchet wheels in mesh with the pawls so that the feed rollers are only rotated as the cartridges are moved toward each other.

20. Apparatus as recited in claim 3 which further comprises: platform means for supporting the article to be tagged; and means for clamping the article on the platform means during the tagging operation.

21. Apparatus as recited in claim 20 which further comprises:

means for moving said platform means into vertical alignment with said securing element passing means; and means for moving said platform means away from vertical alignment with said securing element passing means as the securing element extends through the backup layer and the article.

22. An apparatus for assembling and securing tags to an article, said tags including a threadlike securing element which passes through the article and the ends of which are sandwiched between a backup layer and cover layers, which comprises:

means for horizontally supporting the article;
means laterally spaced from said supporting means for folding a strip of backup material into a generally V-shape;
a needle vertically aligned with said article, said securing

element being carried by said needle;
means for laterally moving said folded, V-shaped strip of backup material so that an edge of the supported article lies in the apex of the V of the strip;
means for clamping the V-shaped strip of backup material around the article, said clamping means having a vertical passageway extending therethrough;
means for moving said needle vertically through said passageway to pass the securing element through the clamping means and article and for then removing the needle leaving the securing element in the article;
means for then moving the article supporting means laterally away from the clamping means to remove the folded strip of backup from the clamp and simultaneously to bend the ends of the securing element toward the edge of the article; and
means for superposing and adhering a cover layer of sheet material over the backup layer on each side to enclose and anchor the ends of the securing element therebetween.

23. Apparatus as recited in claim 22 wherein said moving means is also effective to move the needle and the securing element through the backup layer on either side of the article.

24. Apparatus as recited in claim 23 wherein said backup material folding means comprises:

means for cutting a discrete piece of backup material from an indefinite length of the same;
a vertical guide track defining a slot in which said discrete piece of backup layer material is positioned, said guide member having opposed openings in each side thereof;
a V-shaped shuttle aligned with the openings in said guide track; and
a former punch movable through said openings to fold the backup material into the V of the shuttle.

25. Apparatus as recited in claim 24 wherein said means for clamping the V-shaped strip of backup material includes said V-shaped shuttle and further includes:

a pair of pivoted jaws normally biased apart; and
means for camming said jaws together to fold the discrete piece of backup material around the article.

26. Apparatus as recited in claim 25 which further comprises:

ejector means for positively displacing the folded strip of backup material from the clamp as the article supporting means is laterally moved away from the clamping means.

27. Apparatus as recited in claim 26 wherein said ejector means comprises:

a spring biased pin positioned in the apex of the pivoted jaws; and

50 an actuator mounted on said platform and adapted to be positioned between the ejector and the apex of the V of the pivoted jaws so that movement of the article supporting means laterally away from the clamping means pushes the folded backup layer out of the jaws.

28. Apparatus as recited in claim 27 wherein said actuator is designed to become disengaged from the ejector pin at a predetermined point so that the biased ejector pin can return to the apex of the V of the jaws.

29. Apparatus as recited in claim 23 wherein said needle is hollow and said securing element is positioned on the inside of the needle.

30. Apparatus as recited in claim 23 which further comprises:

means for gripping the leading end of the securing element after said needle moving means has passed the securing element through the article and backup layer so that the securing element remains in that position as the needle is removed.
